UNITED STATES PATENT OFFICE.

PETER A. SCHWAB, OF NEW YORK, N. Y., ASSIGNOR TO ADAMS-WILLIAMS MANUFACTURING CORPORATION, OF NEW YORK, N. Y., A CORPORATION OF NEW YORK.

AUTOMOBILE-BODY CONSTRUCTION.

1,320,101.

Specification of Letters Patent. Patented Oct. 28, 1919

Application filed August 4, 1917. Serial No. 184,513.

To all whom it may concern:

Be it known that I, PETER A. SCHWAB, a citizen of the United States, and resident of New York city, in the county of New York and State of New York, have invented certain new and useful Improvements in Automobile-Body Constructions, of which the following is a specification.

This invention is an improvement in that 10 type of convertible automobiles in which transparent panels having rigid frames may be inserted at will to close the space between the upper edges of the body and the top to convert the automobile to a closed body machine such as a limousine or sedan from an 15 open body machine such as a touring car or runabout. A construction of the general type to which my invention is particularly applicable is shown in the Williams Patent 20 No. 1,151,315 issued August 24th, 1915, although it will be evident that it might be used in other types of construction or for other purposes.

My invention relates particularly to the 25 construction of the horizontal bows or other horizontal members of the top and to which the upper edges of the panels are detachably connected.

The main objects of my invention are to 30 more effectively hold the panels down on their supporting walls, prevent side movement or rattling, conceal the retainers, hold the panels in position even if the retainers should break and provide a simple and inexpensive construction easy to manufacture 35 and assemble and easy to operate in the insertion and removal of the panels.

I may accomplish these objects and carry 40 out my invention in various different ways but preferably the horizontal members of the top are in the form of inverted channels and within the channels are resilient retainers so constructed that they press down on the upper edges of the panels and act not only to hold the upper edges against lateral movement between the side walls of the channel but also to hold the panels down on their supports. In the specific form employed for holding the panels corresponding 45 to the stationary wall sections of the body the retainers permit the upper edge of the panel to be inserted first and permit the entire panel to be raised until the lower edge may be moved laterally to position and 50 lowered into the desired operative engage-

ment with the supporting side wall. This specific arrangement is not employed in connection with the panels carried by the swinging side wall sections of the body, namely 60 the doors.

In the accompanying drawings, Figure 1 is a side elevation showing rather diagrammatically an automobile body, the frame work without the covering of the collapsible top and detachable wall panels; 65

Fig. 2 is an enlarged side elevation showing the upper and lower parts of the panel corresponding to a stationary wall section of the body;

Fig. 3 is a transverse section on the line 70 3—3 of Fig. 2;

Fig. 4 is a view similar to Fig. 3 showing the wall panel with only its upper edge inserted;

Fig. 5 is a perspective view of a portion of 75 the vehicle, a door being open and a part of the horizontal bow of the top being broken away;

Fig. 6 is a side elevation of the upper portion of the door and its retainer; and 80

Fig. 7 is an edge view of the construction of Fig. 6.

I have illustrated my invention in connection with an automobile body having two doors or hinged wall sections 10 and 11, an 85 intermediate stationary wall section 12 and a rear stationary wall section 13. On this body, there is mounted a top, the frame of which includes an upwardly extending pivoted bow 14 and a horizontal bow 15 made 90 up of two sections in alignment with each other and hinged together, the rear section being hinged to the vertical bow 14 and the front section being connected to or rigid with a cross bow not shown. The latter or 95 the front ends of the front section of the side bows may be secured to the side stanchions 16 of the wind-shield. This frame work serves to support a covering of fabric or any other suitable sheet material, which latter may be provided with side sections covering the portion in the rear of the bow 14, and extending forwardly from the latter to the first panel but I have not illustrated such covering as it forms no portion of my 100 invention. So far as the general construction of the frame of the top is concerned, it also forms no portion of my invention. It is only essential that such frame, whether collapsible or rigid, includes a substantially 105 110

horizontal member which is more or less nearly parallel to the upper edge of the side wall of the body.

As an important feature of my invention, 5 I make this horizontal bow 15 or side member of the frame in the form of an inverted channel bent from sheet metal. The transverse sectional form is not particularly important as it may be rounded or flat on the 10 top or sides. As illustrated, the channel has a flat top wall 17 and parallel depending side walls 18 and 19. The side wall 18 is somewhat narrower than the side wall 19 and has an inwardly extending flange or 15 lip 20 at its lower edge. This side wall 18 serves as the outer wall of the bow, that is the side wall outermost on the vehicle. The other or inner side wall 19 is illustrated as being strengthened or reinforced by being 20 bent back upon itself to form a double thickness of metal although this is not essential.

Within the channel there are provided a plurality of resilient retainers. These will differ somewhat as to detail according to 25 whether they are employed in connection with the panel carried by a stationary or a swinging section of the wall. The vehicle illustrated has three of these panels 21, 22 and 23 corresponding in width to the wall 30 sections 10, 11, and 12 of the body and of such height that they extend upwardly from the upper edges of their corresponding wall sections, into the channel in the bow 15.

The retainers used in connection with the 35 stationary panel 23 may be of the form illustrated in Figs. 2, 3 and 4. Within the channel and of a width substantially equal to the width of the latter, I provide one or more blocks 24 mounted to slide substantially vertically within the channel and limited as to downward movement by the in-turned lip or flange 20. The blocks may be 40 of any suitable material although from a practical standpoint I prefer to employ insuated fiber, hard rubber or other similar substance. Each block has a groove or recess in its under surface and of a width substantially equal to the thickness of the upper edge of the panel or some extension on 45 the latter so that the upper edge of the panel may be held against lateral movement when inserted within said groove. This panel is shown as being materially less in thickness than the width of the channel and 50 freely insertible upwardly into the space between the vertical wall 19 and the inwardly directed flange 20. For resiliently pressing the block 24 downwardly and for positioning it, I preferably employ a leaf 55 spring 25. In Fig. 2, I have illustrated a single leaf spring 25 having a block 24 at each end thereof and having its center portion provided with a projection 26 adapted to enter a slight recess or aperture in the top 60 wall of the channel so as to hold the spring 65

and retainer blocks against lengthwise movement. It will, of course, be evident that a rivet or screw could be employed at this point or that a separate spring might be employed for each retainer block and that more or less than two retainer blocks might be employed for each stationary panel. Although the accompanying drawing shows only one such stationary panel, it will of course be evident that with different body designs the number of stationary as well as the number of movable panels will vary.

The range of vertical movement of the blocks 24 is such that the upper edge of the panel may first be inserted in the groove in the under side of the block and may then be raised until its lower edge will swing over its support after which the panel may be dropped down into proper engagement with said support. This interengaging connection between the support and the panel may vary in different construction, but preferably each panel carries two or more depending lugs 27 and the upper edge of the wall has sockets or recesses 28 into which said lugs may be lowered. As shown, the wall 12 has a molding strip 29 thereon in which the sockets are formed and the molding strip also carries clamping screws 30 for engaging with the sides of the lugs to positively hold the lugs and the base of the panel in position. In actual practice in most constructions, these clamping screws are entirely unnecessary where my improved top bow construction and resilient retainers are employed. If the sockets 28 be made of proper size in respect to the size of the lugs 27, the resilient retainers 24 will hold the panels firmly in place and no clamping screws 30 are necessary. It will be noted that the lugs are of such length that when the upper edge of the panel is raised to the limiting position as shown in Fig. 4, the lugs may pass over the top of the molding strip 29 and that after reaching a position above the sockets, the downward movement of the panel and resilient retainers is such that the latter do not engage with the flange 20 and continually exert a downward pressure as well as holding the panel against lateral or jarring movement. When the panel is entirely removed, the retainer will move down until it rests upon the flange 20 but the latter prevents such movement as would permit the retainer to be exposed to view.

The specific form of resilient retainer employed in connection with the panel carried by a hinged wall section, namely a door, is shown more in detail in Figs. 5, 6 and 7. 125 In this construction, there is employed a block 31 and a spring 32 similar in many respects to the block 24 and spring 25 previously referred to. Preferably only a single block is used and the leaf spring is 130.

secured to the top wall of the channel by a screw bolt or rivet 33 which securing means may also be used in connection with the form shown in Figs. 2, 3 and 4. Instead of 5 having the panel extend up into the channel, it is of such height that it may swing beneath the side wall 18 of the latter. The under side of the block 31 carries an extension 34, preferably in the form of a piece 10 of sheet metal bent to appropriate shape. One end of this is secured to the under side of the block wall and the opposite end includes a downwardly facing groove or recess for receiving the upper edge of the 15 panel 21. The spring 32 presses the block and extension 34 downwardly and as the door swings to closed position, it passes beneath the upturned free end of the extension 34 and raises said extension and the block 20 against the tension of the spring 32 until it snaps into position as shown in Fig. 7.

The extension 34 may be of such size and shape that the inturned flange 20 of the channel may serve to limit the downward movement of the block but in practice and 25 to take care of slight variations in the height of panels and the distance between the channel and the upper edge of the door a separate limiting means is preferably employed. As shown, the block 31 has a vertical slot in the outer or free end thereof and a bolt 35 is carried by the top wall of the channel and has its head beneath the block. The block is thus guided vertically by the 30 bolt within the slot and cannot move downwardly farther than is permitted by the head of the bolt. For adjusting this height, the bolt is threaded into the top wall and has a lock nut on its upper end.

40. It will be noted that the block, spring and stop are entirely concealed within the channel and the only part exposed is the narrow extension 34 with its upturned end beneath which the upper edge of the panel moves.

Having thus described my invention, what I claim as new and desire to secure by Letters Patent, is:

1. A vehicle body having a collapsible 50 top including substantially horizontal side bow members in the form of channels having depending side walls, an inturned flange carried by one of said walls, a retainer within said channel, a spring for pressing said 55 retainer down toward said flange, a wall panel having its upper edge held by said retainer, and means for supporting the panel at its lower edge.

2. A vehicle body, having a top including 60 a channel presenting depending side walls, an inturned flange on the lower edge of one of said walls, a resilient retainer including a block within said channel above said flange, and a spring for pressing said block 65 downwardly, said flange serving as a stop to

limit the downward movement of said block, a removable wall panel having its upper edge pressed downwardly and spaced from the walls of said channel by said retainer, and means for supporting said panel at its 70 lower edge.

3. A convertible automobile body, including a wall section, a top having a channel with depending side walls, a removable panel including a transparent sheet and a frame rigid therewith having its upper edge adapted to enter said channel, means within said channel engaging with the upper part of said panel to hold the latter spaced from said side walls, and yieldingly permitting 80 limited vertical movement of the panel in the channel, the lower edge of said panel being movable laterally to a position above said wall section when the upper edge is in maximum raised position in said channel, 85 and interlocking means at the upper edge of said wall section and the lower edge of said panel for preventing sliding or lateral movement of the panel upon the lowering of the 90 panel into seating engagement with said wall section.

4. A convertible automobile body including a wall section, a top having a channel with depending side walls, a panel having the upper edge of less thickness than the distance between said side walls, a resilient retainer within said channel for permitting vertical movement of the panel but engaging with the latter to hold it against lateral movement between the side walls of the 100 channel, and a pair of vertical lugs and co-acting sockets at the upper edge of said wall section and the lower edge of said panel for preventing lateral or sliding movement of the panel, said retainer serving to hold said lugs within said sockets. 105

5. A convertible automobile body, including a wall section, a top having a channel with depending side walls, a panel having an upper edge disposed between said side 110 walls, a resilient retainer within said channel for permitting vertical movement of the panel within the channel, and a pair of vertical lugs and co-acting sockets at the upper edge of said wall section and the lower edge of said panel for preventing lateral or sliding movement of the panel, said retainer serving to hold said lugs within said sockets. 115

6. A convertible automobile body including a wall section, a top having an inverted 120 channel, a block within said channel and having a recess in its under surface, a spring normally pressing said block downwardly, a removable panel having its upper edge adapted to be received within said recess 125 and thereby held against engagement with the side walls of the channel, and a lug at the lower edge of said panel adapted to enter the upper edge of said wall section.

7. A vehicle, having a top including a 130

- channel presenting depending side walls, the lower edge of the inner wall being disposed materially below the lower edge of the outer wall, a vehicle body including a 5 wall portion and a door, a removable wall panel having its lower edge supported by said vehicle body wall and its upper edge within said channel above the lower edge of the outer wall of the latter, and a removable 10 panel secured to said door and having its upper edge beneath said channel and at a lower elevation than the outer wall of the latter but above the lower edge of the inner wall of said channel.
- 15 8. A vehicle, having a top including a channel presenting depending side walls, the lower edge of the inner wall being disposed materially below the lower edge of the outer wall, a vehicle body including a wall portion and a door, a removable wall panel having its lower edge supported by said vehicle body wall and its upper edge within said channel above the lower edge of the outer wall of the latter, a removable 20 panel secured to said door and having its upper edge beneath said channel and at a lower elevation than the outer wall of the latter but above the lower edge of the inner wall of said channel, and separate resilient 25 retainers within said channel for engagement with said panels, the retainer engaging with said door panel permitting the lateral movement of the latter from beneath the channel.
- Signed at New York city, in the county 35 of New York, and State of New York, this 3d day of August, A. D. 1917.
- PETER A. SCHWAB.
